AUTOMATIC FILM PROCESSING MACHINE

Theodore Fonville Winans, Baton Rouge, La.

Application March 6, 1939, Serial No. 260,165

13 Claims. (Cl. 95—39)

This invention relates to a machine for automatically handling articles that require successive treatment in various liquids, and particularly to a machine for automatically processing photographic films and plates.

The processing of photographic films and plates is well-known and usually consists of the following steps: the exposed films or plates are first immersed in a developing solution for a predetermined length of time, determined by the operator; then they are removed from the developer and immersed in a wash solution which will tend to stop its developing action by removing most of the developing solution from the plate or film; the next step is the introduction of the film or plate into a hypo bath where it is fixed to prevent further action of elements used in the developing; the film or plate is now removed from the hypo bath and thoroughly washed with running water; and the final step is the drying of the processed film or plate which is usually accomplished by placing it in a current of warm air. During these various steps it is beneficial to agitate the film or plate to remove air bubbles and to insure uniform contact of the various liquids on the film or plate surface. Since the developing step is the only one that needs to be timed by the operator, the remaining steps can be fixed at some predetermined period of time that will be proper for all films or plates.

The principal object of the present invention is the provision of a machine which will carry a film, secured in a suitable holder, and successively immerse it in different fluids for predetermined periods of time, for its complete processing.

Another object of this invention is the provision of a mechanism for handling and processing films that will automatically pass the films through the various steps of processing and then stop all action until the machine is again charged and set by the operator.

A further object of the invention is the provision of novel means by which the films are moved in an arcuate path from the various trays of a series, and then while in the raised position they are moved by a constantly driven screw-feed to the next adjacent tray and deposited therein by gravity.

Other objects are simplicity and economy of construction, ease and precision of operation, and adaptability for quick adjustment whereby any desired timing is obtained.

Reference will now be had to the drawings wherein:

Figure 1 is a perspective view of an automatic film processing machine embodying this invention.

Fig. 2 is an enlarged plan view of the machine with the covers removed.

Fig. 3 is a vertical sectional view taken on line III—III of Fig. 2.

Fig. 4 is a vertical cross sectional view taken on line IV—IV of Fig. 3.

Fig. 5 is a fragmentary sectional view showing the film holder positioned in one of the containers.

Fig. 6 is a vertical cross section taken on line VI—VI of Fig. 3.

Fig. 7 is an enlarged elevation of the feed-screw and certain of the associated parts.

Fig. 8 is an end elevation of the driving and control mechanism.

Fig. 9 is a fragmentary front elevation of a portion of the control mechanism.

Fig. 10 is a vertical sectional view taken on line X—X of Fig. 8.

Fig. 11 shows the parts disclosed in Fig. 10 moved to another position.

Fig. 12 is a vertical sectional view taken on line XII—XII of Fig. 8.

Fig. 13 is a horizontal sectional view taken on line XIII—XIII of Fig. 8.

Fig. 14 is a diagrammatic showing of the electrical circuit; and,

Fig. 15 is an enlarged detailed view of the trip lever and associated parts.

Throughout the several views like reference characters designate similar parts and the numeral 2 is a cabinet of rectangular shape having a bottom 4, side walls 6 and 8, end walls 10 and 12, and hinged cover member 14. This cabinet 2 is made so as to preclude the light when closed, thus presenting a suitable dark room for the different processing steps.

Removably mounted in cabinet 2 and resting on bottom 4, is a series of trays 16, 18 and 20 secured against horizontal movement by frame 22, which is secured to bottom 4. A stationary water washing tray 24 secured to bottom 4 is connected at its lower portion with water supply pipe 26 connected with a suitable supply of water under pressure (not shown). This pipe 26 is provided with a hand closing valve 27 which is operated as hereinafter set forth.

A waste pipe 28 communicates with the upper portion of tray 24 and leads to a suitable drain outside the cabinet so that water will be maintained at a fixed level in the tray when water is delivered thereto through pipe 26. To facili-

tate proper distribution of the water, a perforated, false bottom 30 is fitted into tray 24 above the water intake opening thereto.

A drier tray 32 is positioned in alignment with the previously mentioned trays and is mounted on the delivery end 34 of an air conduit 36, in such a manner that air from the conduit passes through openings 38 formed in the bottom of the tray. The air conduit 36 communicates with a suitable blower 40 driven by a motor 42. This motor is controlled by special mechanism hereinafter set forth.

In order to prevent the accumulation of excessive air in cabinet 2, outlets 44 are provided in cover 14. Light trap 46 is provided together with black surfaces to prevent the entrance of light during the processing of the films.

Referring now to the film F, it will be noted that it is mounted in a holder 48 having an elongated side member 50 having a notch 52 by means of which it is secured to the carriage, hereinafter described. Any desired number of holders 48 may be provided so long as they can all be introduced into a tray at the same time.

A bar 54 pivotally mounted at its one end in a bearing 56, carried by end member 12, extends through an opening 58 formed in the other end wall 10 of the cabinet and is rotatably mounted in a frame 60. This frame 60 is secured to the outside of end wall 10 and completely covers the opening 58 to preclude light from the cabinet. A housing having stationary end member 62, hinged side 64, hinged end member 66 and hinged cover member 68, serves to completely cover the frame 60 and mechanism associated therewith.

This bar 54 is preferably square in cross section and is adapted to pass through the square hole 72 formed through sleeve 70, whereby the sleeve is secured against rotation relative to the bar. Mounted on sleeve 70 is a U-shaped bracket 73, extending radially from the axis of said bar, and having a cross rod 74 secured thereto in parallel relation with bar 54. This cross rod 74 is adapted to be fitted into the notches 52 of side members 50 to support a series of the film holders 48, see Figs. 3, 4 and 5.

It will be noted that when the holders are in the position shown in Fig. 4, the holders will rest against stop rod 76 carried by bracket 73 to support them in a forwardly extended position, and when moved to the position shown in Fig. 5, side member 50 will move away from stop rod 76 and rest on top of the tray into which the holders are projected, thereby insuring the positioning of the film in fluid contained within the tray. It is quite essential that side member 50 be positioned near the upper edge of the tray to preclude excessive rocking of the film holders on rod 74.

A synchronous motor 78 mounted on the base plate of frame 60 drives shaft 80 which is joined to worm 82 by the connecting sleeve 84. The outer end of worm 82 is reduced at 86 and rotatably mounted in bearing 88 carried by frame 60. Worm 82 intermeshes with a worm wheel 90 which is rigidly secured to and drives a feed screw 92 mounted for rotation in frame 60 and in bearing member 96. This feed screw extends longitudinally through cabinet 2 in parallel relation to bar 54 and serves to move the film supporting carriage along bar 54 at predetermined intervals of time. Positioned above feed screw 92 and in spaced apart relation to said feed screw and bar 54, is a guide bar 94 secured by screws

96 at its one end to frame 60 and at its other end, by screws 98 to bearing member 56.

Securely attached to sleeve 70 of the film carriage by set screws 100, is a member 102 having a tongue 104 and a notch 106, as shown in Figs. 2, 3, 5 and 6. Member 102 can also be made integral with the sleeve.

Tongue 104 is preferably arcuate at its lower portion 105 to operatively engage feed screw 92 which is constantly driven by the synchronous motor 78. Guide bar 94 is notched at 108, 110, 112, 114 and 116 to permit tongue 104 to be moved thereabove and below as the films are moved to or from the various trays.

It is the purpose of the guide bar 94 to secure the tongue 104 in operative engagement with feed screw 92 during the movement of the film carrier from one tray to the next, and it will be noted that the notches in guide bar 94 are positioned respectively, substantially centrally there-with so that the films will be properly guided to and from the respective trays.

In order to position the tongue 104 in operative relation with the feed screw 92, when the films are positioned in the carrier above the developing tray 16, it was found necessary to provide a latching means comprising a member 118 rotatably mounted in bearings 120 carried by guide bar 94. The inner end of 118 is offset to form an oscillatable finger 122 which is positioned in alignment with the center position of notch 108. The other end of member 118 is formed transversely of its axis of rotation to provide an operating arm 124. Spring 126 engages member 118 to constantly urge finger 122 toward feed screw 92.

Referring to Fig. 4 the film carriage is shown in the raised position with the tongue 104 in engagement with the feed screw 92 and with the finger 122 resting on tongue 104 to maintain the carrier in the raised position, against the weight of the carrier. The center of gravity of the carrier is to one side of the vertical line extending from the supporting bar 54 so that when the tongue 104 is released by operating arm 124, the carrier will, by the action of gravity, move to the position shown in Fig. 5.

To prevent too rapid downward movement of the film carriage, a retarding mechanism comprising an arm 128 rigidly secured to bar 54 by set screw 130 and connected by pin 132 to piston rod 134 of dash pot 136. This dash pot is pivotally connected at 138 to bracket 140 carried by cabinet 2. This dash pot can be adjusted to properly control the downward movement of the carrier, regardless of its weight. The slot 142 in rod 134 permits a limited oscillation of the bar 54 independently of the dash pot.

The water supply control, best shown in Figs. 2, 3, 6 and 7, includes a valve 144 in the water supply pipe 26. This valve can be of the automatic spring closing type, but in order to clarify the showing, tension spring 146 is shown attached to valve lever 148 and to a stationary pin 150 and tends to constantly urge the valve to the closed position, shown in Fig. 3. Attached to valve lever 148, by bolt 152, is a bracket 154 having a transverse rib 156 against which a valve lever 158 pivoted at 160 to bracket 154, rests. This lever 158 is positioned and pivoted for transverse movement relative to the oscillatory movement of valve lever 148 and extends above a plate 162 carried by guide bar 94. This plate is provided with a notch 164 into which the upper end of lever 158 is urged by spring 166 as the valve is

in the open position. A horizontally disposed lever arm 168 pivoted intermediate its ends by pin 178 to plate 162, normally rests in the position shown in Fig. 7, with its one end 172 in alignment with notch 164 while its other end 174 extends into the path of travel of carrier tongue 164 by which it is operated to cause lever end 172 to force the lever 168 from notch 164 against the action of spring 166 so that the tension spring 166 will move the valve 144 to the closed position.

It will be noted that the spring 166 constantly urges the upper end of lever 168 against the longitudinal edge 176 of plate 162. The tongue 164 in its travel from notch 112 to 114 during the operation of the machine, engages the end of lever 168, moves it to engage notch 164 and then when the tongue is moved from notch 114 to 116 it contacts and forces end 174 of lever arm 168 outwardly thereby causing lever end 172 to release valve lever 168 from notch 164.

In order to facilitate proper drying of the films in tray 32, it has been found best to cover the liquid containing trays 16, 18, 20 and 24, with a suitable cover 177 pivoted at 178 to side wall 8, when the drying operation is about to begin. The cover is normally secured in the raised position by latch member 180 secured for oscillatory movement to side wall 8 by screw 182. The operator moves the cover 178 to the open position and sets the latch in the position shown in Figs. 2 and 6, with the lower arm 184 of the lever in the path of travel of the extended side 50 of the film holder, so that as the film carrier is being lowered into the drying tray, 32, it will move the latch engaging portion 186 from in front of the cover. When the latch is thus operated kick spring 188 urges the cover 178 to the closed position to cover all except the drying tray. When the machine is recharged, the operator again secures the cover in the open position.

Reference will now be had to the timing mechanism whereby the time periods of various processing operations are determined. For a typical example, it will be considered that in the processing of a film the operator determines from his technical knowledge that the particular film requires six minutes (6 min.) in the developing solution. He sets the mechanism, hereinafter described, to said time period, and the other operations being more or less standard and fixed, are each given the proper period of duration, thus making it possible by a single setting of the machine to obtain proper developing, rinsing, fixing, washing and drying. After the machine has been loaded and the developing time set, the film will be completely processed, ready for printing, without any further attention of the operator.

The synchronous motor 18 operates at a substantially constant speed to drive feed screw 82 at a reduced rate of speed. This feed screw 82 is provided with worm 188 which intermeshes with and drives a worm gear 182 mounted on a vertical shaft 184, mounted for rotation in bearings 186 and 188, carried by frame 80. A further reduction of speed is obtained by providing a worm 200 on shaft 184 which in turn, drives worm gear 202, mounted on shaft 204, rotatably mounted in bearings 206 and 208, carried by frame 80. Worm 210 rotatable with shaft 204 drives worm gear 212, which is securely mounted on shaft 214. This shaft 214 is mounted in bearing 216 carried by frame 80 and extends therefrom to receive an operating disc 218 mounted

for free rotation relative thereto and also to receive a frictionally mounted shaft extension 218, which is adapted to extend through an opening 220 formed through side member 64, and through a dial member 222 secured to the outside surface of member 64.

The outer end of shaft extension 218 is provided with an operating knob 224 and an indicator hand 226 which is adapted to be positioned to indicate time intervals on a graduated index 10 228 on dial member 222. Extension member 218 is tubular in form and slotted at its inner end as at 230, and is formed to frictionally grip the end of shaft 214. To prevent longitudinal movement of shaft 214 a collar 232 secured by pin 234, 15 rests against bearing 216 while the hub of worm wheel 212 contacts frame 60.

A finger 236 carried by shaft extension 218 is adapted to be driven in a clockwise direction to contact pin 238, extending outwardly from 20 disc 218, thereby causing the disc 218 to rotate in a clockwise direction.

The operating disc is provided at its periphery with radially extending fingers 240, 242, 244 and 246. The spacing of these fingers is determined by the time of respective steps of processing that they control. The indicator hand 226 is timed to make one complete revolution per hour so that when finger 236 engages pin 238, operating disc 218 will be rotated at a like rate of 30 speed to properly time the different steps of the film processing.

As stated above, the bar 54 is oscillated to cause the movement of the film carriage to and from a position within the various trays. This oscillation is obtained by the following mechanism (see Figs. 8, 9, 10, 11, 12 and 13.).

A miter gear 248 is secured for rotation with shaft 194 by spline 250 which permits of relative longitudinal movement. This miter gear 248 is 40 adapted to be moved to and from intermeshed relation with miter gear 252, securely mounted on shaft 254 rotatably mounted in bearing 256 by the following mechanism.

A yoke consisting of shaft 258 mounted for 45 rotation in bearings 260 carried by frame 80 is provided with radially disposed arms 262, carrying oppositely disposed engaging fingers 264, adapted to engage annular groove 264 formed in the hub of miter gear 252. An arm 266 secured to shaft 258 by set screw 268, is pivoted at its lower end to a lever 270. This arm is held in a substantially horizontal position against the lower side of a stationary detent 272 carried by frame 80, by diagonally disposed tension spring 55 274 secured at its one end to arm 266 and at its other end to lever 270. Notch 276 formed in the upper side of lever 270 presents a shoulder 277 which rests against detent 272 to normally secure miter gear 252 in the disengaged position against 60 the action of spring 274. It will be noted that 272 has a notch 278 into which lever 270 is positioned to prevent transverse movement thereof.

As clearly shown in Figs. 8 and 15, the outer end of lever 270 is angled upwardly and provided with an operating finger 278 pivoted at 280 and provided with transversely projecting lugs 282 and 284 which are adapted to engage opposite sides respectively of projection 286 integral with lever 270. These lugs are so spaced apart as to 70 allow a slight oscillation of the finger 278 relative to lever 270 for reasons hereinafter set forth. A tension spring 288 attached at its one end to lever 270 and at its other end to finger 278 maintains the outer end of the finger 278 in the raised 75

position with lug 286 contacting projection 286. It will be noted that when the miter gear 252 is being held in the raised position and lever 270 is in the extended, latched position, finger 278 5 will be in the path of travel of the disc fingers 240, 242, 244, and 246, so that as disc 218 is rotated and one of these fingers contacts finger 278, it will be oscillated on its axis to extend spring 274 until lug 282 contacts projection 286, then lever 10 270 will move downwardly until it is released from detent 272. When the lever 270 is released spring 274 contracts and moves finger 278 out of the path of travel of the operating fingers and also through interconnecting mechanism 15 described above, causes miter gear 252 to operatively engage miter gear 248 and cause it to rotate through a given arc. As soon as finger 278 is retracted, spring 288 will retract and cause the finger to be raised until lug 284 strikes projection 20 286, thereby making it possible to return the finger to a position in the path of travel of the operating fingers 240, etc., without striking the operating finger which just moved the finger 278 to the released position.

25 Referring to Figs. 10, 11 and 13, it will be noted that shaft 254 is provided at its outer end with a radially extending pin 380 which engages pin 382 and drives arm 290, which is mounted for rotation on shaft 254, and adapted to rotate in 30 the direction of the arrow as long as the driven pin 380 engages pin 282.

An arm 292 rotatably mounted on bar 54 is slotted at 294 and interconnected by link 296 to arm 290 by pins 298 and 300 respectively. 25 Arm 292 is slightly longer than arm 290 thus insuring an oscillatory motion of arm 292 as arm 290 rotates in one direction. Pins 380 and 382 are normally positioned as shown in Fig. 10 in spaced apart relation to permit rapid independent movement of lever 290 to its normal position. Rigidly secured to bar 54 by set screw 302 is an arm 304 carrying a pin 306 in the path of travel of arm 292. The normal position of these parts is clearly shown in Fig. 10, while 45 in Fig. 11, the arm 292 is shown moved upwardly to contact pin 306 to rotate bar 54 through arm 304. The amount of rotation of bar 54 can be fixed by adjusting arm 304 on bar 54 to vary its relation to arm 292. As arm 292 is rotated in 50 50 a clockwise direction, as shown, it tensions a spring 308 attached at its one end to a pin 310, carried intermediate the ends of lever 292, and at its other end to a stationary part of frame 60. This spring returns the arms 292 and 290 to 55 their normal positions after they have passed their center line of movement and gears 248 and 252 will be disengaged by the following mechanism. A lever arm 312 rigidly secured to shaft 258 is moved to a position in the path of travel of the arm 290 when the miter gears 248 and 252 are in mesh, and after the arm 292 has been moved to oscillate bar 54. Arm 290 will engage lever 312 and force it to oscillate shaft 60 65 258 and position lever 270 with notch 276 engaging detent 272 and the miter gears will be secured in the disengaged relation. When lever 292 has returned to its normal position, the bar 54, with its associated parts, will be free to return 70 to its normal position with the film carrying member in position in one of the series of trays, as previously described.

75 Bar 54 is also provided with a lever arm 314 which is adjustably secured thereto by set screw 316. This lever is offset at 317 and provided

with an oblique surface 318 which is adapted to be moved to a position in the path of travel of lugs 320 carried on the upper face of the worm gear 192 which is constantly rotated in one direction when the machine is in operation. 5

Whenever one of the lugs 320 passes under the offset portion of lever 314, the bar 54 will be oscillated through a slight arc, thereby causing the film carrying member to agitate the liquid in tray or to shake the liquid from the surface 10 of the films before the drying operation.

Set screw 316 is positioned in the vertical position when the film holder is lowered into the tray as described above, so that it is adapted to serve as a hand grip whereby the operator may 15 oscillate bar 54 to cause a movement of the films in the solution contained in the tray 16.

Referring now to the timing disc 218 and its associated parts, it will be noted that in Figs. 8 and 9 the parts are positioned to correspond with the position of the film carrying member, shown in Fig. 4. The finger 236 has been set by positioning hand 226 at the index denoting six minutes (6 min.) period of time. Finger 236 will engage pin 238 on disc 218 thereby causing 25 finger 240 to engage operating finger 278 and release lever 270, thereby putting in motion the mechanism, previously set forth, to remove the film carrier member from the solution in the developer tray. The tongue 104 then engages feed screw 92 and the film carrier member is moved to a position above the tray 18, and released when tongue 104 registers with notch 110. The weight of the film carrier member causes 30 it to move downwardly into the tray 18 where it will remain until the finger 242 moves to again release the latched lever 270. These operations will be repeated by the action of fingers 244 and 246 after which the film carrier member 35 will be positioned in the drying tray 32. 40

When the film carrying member is being moved from the hypo tray 20 to the rinsing tray 24, the water supply is turned on to provide flowing water for the washing operation, also when the films are moved from tray 24 to the drying tray 32, the water supply is cut off, by mechanism 45 previously described.

A short period after the film carrying member has been positioned in the drier tray 32 and has been jolted by the action of lugs 320, then the air is turned on by the following means. Referring to Figs. 8, 9 and 14, it will be noted that a switch lever 322 pivotally mounted at 323 on standard 324 is maintained in a normal position, as shown in Fig. 9, by means of a tension spring 326 which holds it against the stop pin 328. Switch lever 322 carries two mercury switch members 330 and 332. Switch 332 is normally closed since the mercury joins the two contact points 334 and 336 and switch 330 is normally open since the mercury does not join the contact points 338 and 340. An operating pin 341 mounted on disc 218 moves to contact the upper end of switch lever and move it to a position so that the mercury switches will be tilted sufficiently to close switch 330 and open switch 332. This operation of switch lever 322 takes place after finger 246 has operated the lever 270, described above. 55

60 A time delay switch 342, set forth in U. S. Letters Patent No. 1,773,697, is mounted in end member 62 and is adapted to be set for any desired period of time.

65 Referring now to the diagrammatic showing 70

of the electric circuit shown in Fig. 14, the numerals 348 and 358 designate electrical supply wires. Wire 352 joins wire 358 to one of the poles 354 of the time switch 342, and the other pole 356 of switch 342 is connected by wire 358 to contact point 348 of switch member 338, also wire 358 joins wire 358 to contact point 334 of switch 332 with the time switch 342.

The other contact point 336 of switch 332 is joined to one side of motor 78 by means of wire 362. The other side of motor 78 is connected by wire 364 to wire 358 leading from wire 348 to one pole of the blower motor 42. The other pole 368 of motor 42 is connected with contact point 338 of switch 332 by wire 370.

The flow of current in circuit is as follows: switch 342 is first set to and closed so as to remain closed for a predetermined period of time, sufficient to carry out the complete processing 20 of a film. When so closed with the switch 330 open and switch 332 closed, the current from wire 358 passes through wire 352, switch 342, wires 358 and 360, switch 332, wire 362, motor 78, wires 364 and 366 to wire 348. When switch 330 is closed and switch 332 is opened, as described above, the current flow is as follows: wire 350 through wire 352, switch 342, wire 358, contact points 338 and 348, wire 370, through motor 42 and wire 366 to line wire 348. After a predetermined period of time of operation of the blower motor 42, the time switch 342 operates to open the circuit, thereby cutting off all current to the motors, thus stopping the action of the machine.

It is very apparent that time periods of the different steps in processing films or the handling of any other object requiring different timed steps of processing, may be obtained by replacing timing disc 218 with any other suitable disc 40 having the various fingers and pins spaced to correspond to the desired time periods. Also the speed of rotation of disc 218 may be easily varied without changing the general construction of the device.

The cabinet 2 might be dispensed with and the mechanism could be suitably positioned in any dark room, furthermore, the device might be used where no exclusion of light is required.

The notch 106 in member 102 is adapted to receive guide bar 84 when the parts are in position to permit the return of the film carriage from the drying tray to the developing tray.

By means of the hand operated valve 27, the supply of water to the washing tray may be definitely determined.

A heating unit 380 positioned in the air supply system, see Fig. 8, is adapted to properly warm the air that is supplied to the drying tray, also 60 perforations 392 in motor housing serve to allow circulation of air sufficient to properly ventilate the motors 42 and 78.

Having thus described the invention, what is claimed as new and desired to be secured by Letters Patent is:

1. A machine for processing films comprising a series of trays; a film carrying member mounted for movement longitudinally of said series of trays, on an oscillatable bar; time controlled means operable to oscillate said bar to move said film carrying member successively from said trays; a constantly driven feed screw adapted to engage and move said film carrying member from one tray to the next adjacent tray; and means whereby said carrying member is re-

leased from said feed screw and dropped into said adjacent tray.

2. A machine for handling films and the like, comprising a series of longitudinally disposed trays; a film carrying member slidably mounted on an oscillatable bar for oscillation therewith; time controlled means operable to oscillate said bar, at variable predetermined intervals, to move said film carrying member from said trays; and constantly driven means whereby said film carrying means is engaged and moved longitudinally on said oscillatable bar from one tray to another.

3. A machine for handling films and the like, comprising a series of trays adapted to receive said films; a film carrier member slidably mounted on and oscillatable with an oscillatable bar; time controlled means operable to oscillate said bar at predetermined intervals whereby said film carrying means is moved from said trays; and constantly driven means whereby said film carrying member is moved in one direction from one tray to another when said carrying means is positioned outside the tray.

4. A machine for handling films or the like, comprising a series of trays adapted to receive said films; a longitudinally disposed bar rotatably mounted adjacent said trays; a film carrier member slidably mounted on said bar and secured against rotation relative thereto; time controlled means operable to oscillate said bar at predetermined periods of time whereby said film carrier is moved from said trays; and a feed screw adapted to engage and drive said film carrier from one tray to the next adjacent tray.

5. A machine for handling films or the like, comprising a series of trays adapted to receive said films; a film carrier member slidably mounted on and oscillatable with an oscillatable bar; a constantly driven feed screw positioned adjacent said trays; time controlled means operable to oscillate said bar at predetermined intervals of time whereby said film carrier member is successively moved from said trays to engage said feed screw for movement longitudinally of said series of trays; and means associated with said time controlled means, operable to agitate said film carrier member as it is positioned in the various trays.

6. A machine for handling films or the like, comprising a series of trays adapted to receive said films; a film carrier member slidably mounted on and oscillatable with an oscillatable bar; a constantly driven feed screw positioned adjacent said trays; time controlled means operable to oscillate said bar at predetermined intervals of time whereby said film carrier member engages said feed screw and is successively moved from one tray to another; and means associated with said time controlled means whereby said film carrier member is intermittently moved through a relative short distance whereby it is agitated within the various trays.

7. A machine for handling films or the like, comprising a series of aligned trays adapted to receive said films; a film carrier member slidably mounted on and oscillatable with an oscillatable bar aligned with said series of trays; a feed screw, rotatably mounted in parallel relation with said oscillatable bar; a guide bar having spaced apart notches formed therein, carried in parallel, spaced apart relation to said feed screw; timed controlled means operable to move said film carrier member from said trays and to position a tongue, contained thereon, in engagement with said feed

screw, whereby it is fed between the feed screw and said guide bar to the next notch in the guide bar.

8. A machine for handling films or the like, comprising a series of aligned trays adapted to receive said films; a film carrier member slidably mounted on and oscillatable with an oscillatable bar aligned with said series of trays; a feed screw, rotatably mounted in parallel relation with said oscillatable bar; a stationary guide bar, having spaced apart notches formed therein, carried in parallel, spaced apart relation to said feed screw; timed controlled means operable to move said film carrier member from said trays, and to move 10 a tongue portion thereof, through one of the notches formed in said guide bar, to engage said feed screw, whereby the film carrier member is moved to a position above the next adjacent tray.

9. A machine for handling films or the like, 20 comprising a series of aligned trays adapted to receive said films; a film carrier member slidably mounted on and oscillatable with an oscillatable bar aligned with said series of trays; a feed screw, rotatably mounted in parallel relation with said oscillatable bar; a stationary guide bar, having spaced apart notches formed therein, carried in parallel, spaced apart relation to said feed screw; timed controlled means operable to move said 25 film carrier member from said trays, and to move a tongue portion thereof, through one of the notches formed in said guide bar, to engage said feed screw, whereby the film carrier member is moved to a position above the next adjacent tray; and retarding means whereby the speed of down- 30 ward movement of the tray carrier member into the adjacent tray is regulated.

10. A machine for handling films or the like, 40 comprising a series of aligned trays; a valve controlled liquid supply system communicating with a certain one of said trays; a film carrier member slidably mounted on and oscillatable with an oscillatable bar; time controlled means operable to move said film carrier member successively from one tray to the next adjacent tray, said 45 means being adapted to open the valve of said

liquid supply system as said film carrier member is moving to said certain tray and to cause the closing of the valve when the film carrier member is moved away from said certain tray.

11. A machine for handling films, or the like, 5 comprising a series of aligned trays; a motor driven air compressor communicating with a certain one of said trays; an oscillatable bar extending in parallel relation with said aligned trays; a film carrier member slidably mounted for oscillation with said bar; time controlled means to successively move said film carrier member in one direction to each of the trays of the series; and means controlled by said time controlled means to cause said compressor to deliver a flow 10 of air to said certain tray when the film carrier member is positioned therein.

12. A machine for handling films or the like, comprising a series of aligned trays adapted to receive said films; an oscillatable bar mounted for 20 oscillation adjacent said series of trays; a constantly driven feed worm positioned in parallel relation with said bar; time controlled means to move said film carrier holder from the successive, predetermined time periods, into engagement 25 with said driven feed worm; and means to secure said carrier member and feed worm in operative relation as the carrier member is being moved between adjacent trays.

13. A machine for handling films or the like, 30 comprising a series of trays adapted to receive said films; a film carrier member having means for supporting a plurality of films in spaced apart relation; an oscillatable bar extending longitudinally of said series of trays and serving as a 35 sliding support for said film carrier member for oscillation therewith; time controlled power means whereby said bar is oscillated through different degrees; a constantly driven feed screw adapted to contact and drive said film carrier member from one tray to another, as it is at its highest point of oscillation; and means to force air through one of said trays after said time controlled power means has been made inactive.

THEODORE FONVILLE WINANS.
